W. H. G. GEAKE

DISPENSING CONTAINER

Filed June 29, 1926

FIG. 1.
FIG. 2.

INVENTOR.
W.H.G.GEAKE.

BY *Johnston, Haugh & Co.*
ATT'YS.

UNITED STATES PATENT OFFICE.

WILLIAM HENRY GREGORY GEAKE, OF KILLARA, NEAR SYDNEY, NEW SOUTH WALES, AUSTRALIA, ASSIGNOR TO WALTER RUTHERFORD, OF LONDON, ENGLAND, AND JOHN BAIN, OF OTTAWA, CANADA.

DISPENSING CONTAINER.

Application filed June 29, 1926. Serial No. 119,458.

This invention relates to improvements in dispensing containers, and the objects of the invention are to provide a simple and effective form of container for dispensing various materials such as paste, plastics, creams, etc., in which the dispensing mechanism will be of the simplest possible character and yet operate to positively dispense convenient quantities of the material for use as may be required.

Further objects of the invention are to provide a container which may be manufactured in large quantities at low cost and be adaptable for use in various proprietary articles which are sold in containers used by the consumer for dispensing purposes.

In this construction, the invention includes a container having a suitable orifice or dispensing nozzle, a follower therein formed of resilient material such as cork, and a spring propelling member adapted by turning of the cover or other member on the container to actuate the follower to dispense the material. Other features of the invention will appear from the following specification, all constructed and arranged as shown in detail in the accompanying specification and drawings.

In the drawings:

Figure 1 is a sectional elevation of one embodiment of the invention;

Figure 2 is a sectional elevation of an alternative form of the invention;

Figure 3 is a sectional elevation of another alternative form of the invention;

Figure 4 is a section through the follower member;

Figure 5 is a section showing an alternative form of container.

In the drawings, like characters of reference indicate corresponding parts in all figures.

Referring to the drawings, A indicates a suitable form of container of any convenient shape. The container may be made from a variety of kinds of materials selected with reference to the material to be contained therein. It may, for instance, be made of thin sheet metal, celluloid, glass, cardboard, paper, vulcanite, etc. The container in the embodiment illustrated is of cylindrical form enclosed at one end with a cap B having a flange 10 fitting over the cylindrical side 11

of the container. The container or the cap is provided with an orifice through which the material may be extruded.

In the embodiment shown in Figure 1, a dispensing nozzle 12 is provided about the orifice 13. C indicates a follower or pressure member mounted after the manner of a piston in the container C and conveniently formed of resilient material which will enable a tight joint to be made with the inner walls of the container and will also form an operative connection between the propelling member D and the follower member C. I have found that cork is a very suitable material for use in the follower member. I have found further in using such material that it is desirable to provide sealing means between the member and the walls of the container, and I conveniently effect this by a layer or coating of wax 14 on the surface of the follower member, a portion of which extends down into the joint between the follower and the inner walls of the container.

The propelling member D is conveniently helical in form, and I provide a very simple connection between the propelling member and the follower C by merely forcing the propelling member through the follower after the manner of a corkscrew, whereby the propelling member will extend through a helical passage in the propelling member. I find it in such a case desirable to lock the propelling member and the follower member together, also to re-enforce the follower member by a transverse pin 15 which extends between two coils of the spiral. The propelling member D is preferably in the form of a spring, the spring characteristics performing the additional function which will be hereafter described. One end of the propelling member D is fixedly connected to the underside of the cover B, the latter being rotatable, connection being preferably made immediately adjacent to the orifice 13. The opposite end of the propelling member D may extend adjacent to or against the bottom 16 of the container, which bottom may be provided with a small orifice 17 designed to admit or to prevent the formation of a vacuum.

When the container is filled with material the follower member is preferably adjacent to the bottom thereof. The material is filled

in the container after which, when the cap or member B is turned, the propelling member D will also be turned and this, extending spirally through the follower C, will draw 5 the follower towards the cover and so extrude the material through the aperture 13. It will be observed that the spring in the member D will serve to hold the cap in position on the container A, and it may also be 10 observed that the spring may be so designed, if desired, that a certain amount of extrusion will take place after turning of the cap or cover. That is to say, during the movement of the cover B the spring will both be unwound and turned through the member C. Upon completion of the movement of the cap B the spring will rewind, causing continued movement of the follower C. Whether or 15 not this additional following movement is 20 desirable would depend upon the character and consistency of the material within the container, but the spring arrangement of the follower member enables the result to be obtained when desired.

25 The helical spring form of the propelling member D also enables the same to be used as a closure or valve for the material to be extruded. This may be accomplished by forming a portion of the spring more closely 30 wound than the remainder, whereby, during a portional movement, such closely wound portion will open to permit the extrusion of material therethrough.

In the alternative form of the invention 35 shown in Figure 2, I have shown a closely wound portion 18 on the spring propelling member D'. It may be so designed that before movement the portion D' will be completely closed in such a way that the material 40 may not pass from the outside to the inside of the helix and thus to the opening 13. In such an event it will be desirable to close off the remainder of the helix from the material in the container, which may be done by providing a filling member 19 extending within 45 the member D' from the bottom to the point where the closely wound portion 18 of the helix begins. In this event a cylindrical aperture 20 will be provided through the follower member C, the outer turns of the helix 50 engaging a suitable spiral groove 21 in the wall of the opening 20. In operating this form of the invention the first portion of the turning movement of the cap B will cause 55 the opening of the closely wound portion 18. Continued movement will cause movement of the follower member C which will force the material in the container between the

coils of the portion 18 and out through the orifice 13.

60 Figure 3 shows a modification of the form shown in Figure 2, the cut-off in this case being formed by a valve plate 22 immediately below the orifice 13 and resting on top of the central portion 23 of the spiral spring D². The top of this spring is provided with a few extra wider turns 24 which are connected to the underside of the cap B at a point beyond the opening 13. In this form 65 of the invention the initial movement of the cap D will cause tightening of the centre portion 23 of the spring D², thus drawing the valve plate 22 away from the opening 13 and permitting the material to be extruded. Continued movement will draw up the follower C towards the cap and cause continued 70 extrusion of the material.

75 An alternative form of container A' has 80 corrugated walls, and in this event the follower member itself may be left in cylindrical shaped corrugations, being filled in by means of wax sealing material, which material will spread to fill in all crevices or openings between the follower and the wall of the 85 container.

90 As many changes could be made in the above construction and many apparently widely different embodiments of my invention, within the scope of the claims, constructed without departing from the spirit or scope thereof, it is intended that all matter contained in the accompanying specification and drawings shall be interpreted as 95 illustrative and not in a limiting sense.

95 What I claim as my invention is:

1. In combination, a container having an orifice, a follower therein, and a spring member operatively connected to the follower adapted, when turned, to move the follower axially of the spring, said spring having a 100 closely wound portion through which the material is forced when opened.

2. In combination, a container having an orifice, a follower therein, and a spring member operatively connected to the follower adapted, when turned, to move the follower axially of the spring, said spring having a 105 closely wound portion through which the material is forced when opened, and means for closing off a portion of the spring 110 so that material may only pass through the closely wound portion.

110 In witness whereof I have hereunto set my hand.

WILLIAM HENRY GREGORY GEAKE.
